JOHAN PARTMANN, OF NEW YORK, N. Y., ASSIGNOR OF ONE-HALF TO JOHN NAGY, OF NEW YORK, N. Y.

LOCK FOR HAND-BAGS.

1,113,821.

Specification of Letters Patent.

Patented Oct. 13, 1914.

Application filed October 25, 1913. Serial No. 797,206.

To all whom it may concern:

Be it known that I, JOHAN PARTMANN, a subject of the King of Hungary, and a resident of the city of New York, borough of Bronx, in the county and State of New York, have invented a new and Improved Lock for Hand-Bags, of which the following is a full, clear, and exact description.

My invention has for its object to provide an improved lock for hand bags, having a stud mounted on a frame member of the hand bag, this stud having at opposite sides, bearings in which the terminals of a handle are journaled, there being a tongue secured to the companion frame member, for movement in a recess in the stud, so that the terminal of a bolt member disposed for moving in a hollow portion of the handle and in a guideway in the stud, may move into an opening in the tongue to hold the tongue relatively to the stud and with the frame members together. In the handle there is a slot through which a pin is disposed, this pin being secured to a ring for movement on the handle and to the bolt member for moving the bolt member away from the tongue against the resiliency of a spring.

Still other objects of the invention will appear in the following specification, in which the preferred form of the invention will be found described.

In the drawings similar reference characters refer to similar parts in all the views, in which—

Figure 1 is a view showing in elevation my improvement, parts being broken away to show the construction; Fig. 2 is an enlarged fragmentary sectional view of the improvement; Fig. 3 is a sectional view on the line 3—3 of Fig. 1; Fig. 4 is a sectional view on the line 4—4 of Fig. 1; and Fig. 5 is a sectional view on the line 5—5 of Fig. 1.

By referring to the drawings, it will be seen that the bag 9 has the usual frame members 10 and 11, at its mouth, these frame members 10 and 11 being adapted to be opened, so that the interior of the bag may be reached. To the frame member 10, there is secured a stud 12 and to the frame member 11, there is secured a standard 13, having a tongue 14 for moving in a recess 15 in the stud 12, the tongue 14, being provided with an opening 16, for receiving a terminal 17 of a bolt member 18, provided for

moving in the hollow handle 19 and in the guideway 20, which connects the interior of the hollow handle 19 with the recess 15. It will therefore be seen that when the terminal 17 of the bolt member 18, extends through the opening 16 in the tongue 14, it will serve to hold the tongue 14 relatively to the stud 12 and with the frame members 10 and 11 together. The terminal 17 of the bolt member 18 is received in a notch 21, in the stud 12, after it passes through the opening 16 in the tongue 14.

As has been stated, the bolt member 18 is disposed in the hollow handle 19, this hollow handle 19, having terminals 22 and 23, which are disposed in openings 24 and 25 at opposite sides of the stud 12, the terminals 22 and 23 having pins 26 for rotating in grooves 27 in the stud 12, the terminals 22 and 23 of the handle 19, being prevented from movement away from the stud 12 by the engagement of the pins 26 in the grooves 27. The bolt member 18, extends to a point adjacent the top of the handle 19, a pin 28, being secured to the bolt member 18 and extending through slots 29 in the handle 19, the terminals of this pin 28, being secured to a ring 30, so that the bolt member 18 may be readily moved, that its terminal 17 may be freed from the tongue 14 at the opening 16 therein. The bolt member 18 is held yieldingly in the position shown in Fig. 2 of the drawings, by a spring 31, one end 32 of which presses against the pin 28, the other end 33 of the spring being held in position by a pin 34.

By referring to Figs. 2 and 5 of the drawings it will be seen that there are guideways 35 at the bottom of the stud 12 which extend outwardly from the grooves 27 and that the pins 26 which are normally disposed in the grooves 27 at a distance from the guideways 35 may be rotated with the handle 19 to positions in alignment with the guideways 35 when the terminals 22 and 23 may be moved away from each other, the pins 26 moving outward in the guideways 35 to free the handle from the stud 12.

Having thus described my invention, I claim as new and desire to secure by Letters Patent:

1. A bag having two frame members, a stud on one of the frame members and provided with bearing openings at opposite ends, there being in the stud circular grooves

- communicating with the bearing openings and guideways extending outwardly parallel with the axes of the bearing openings from the circular grooves to the ends of the stud, a handle having a hollow terminal and a second terminal, the terminals of the handles being provided with pins for moving in the guideways and for rotating in the circular grooves, there being a recess in the stud 5 extending through the outer surface of the stud between the said ends, the stud having a guideway extending from the hollow terminal of the handle to the recess, a tongue on the other frame member and provided 10 with an opening, a bolt in the hollow terminal of the handle for movement through the guideway and into the opening in the tongue, and means for moving the bolt relatively to the handle.
2. A bag having two frame members, a stud on one of the frame members with bearings at opposite sides, a handle having a hollow terminal and a second terminal, the terminals being journaled in the bearings, 15 there being a recess in the stud extending through the outer surface of the stud between the said sides, the stud having a guideway extending from the hollow terminal of the handle to the recess, a tongue on the other frame member and provided with an opening, a bolt member in the hollow terminal of the handle for movement through the guideway and into the opening in the tongue, there being a slot in the side of the 20 hollow portion of the handle, a pin secured to the bolt member and extending through the slot, a ring for movement on the handle, to which the pin is secured, and resilient means for holding the bolt member yielding 25 relatively to the handle.
3. A bag having two frame members, a stud secured to one of the frame members and provided with a recess, a hollow handle secured to the stud, there being a guideway 30 in the stud extending from the recess to the hollow portion of the handle, a tongue with an opening secured to the other frame member for movement in the recess, a bolt member in the hollow handle for movement in 35 the hollow portion of the handle, a pin secured to the bolt member and extending through the slot, a ring for movement on the handle, to which the pin is secured, and resilient means for holding the bolt member yielding 40 relatively to the handle.
4. A bag having two frame members, a stud secured to one of the frame members and provided with bearing openings at opposite sides, there being in the stud circular 45 grooves communicating with the bearing openings and guideways extending outwardly parallel with the axes of the bearings from the circular grooves to the ends of the stud, a handle having terminals with pins for movement in the guideways and for rotating in the circular grooves, and means for securing the other frame relatively to the stud.

the guideway and into the opening in the 50 tongue, there being a slot in the side of the hollow portion of the handle, a pin secured to the bolt member and extending through the slot, a ring for movement on the handle and to which a pin is secured, and resilient 55 means for holding the bolt member yielding relatively to the handle.

4. A bag having two frame members, a stud secured to one of the frame members and provided with bearing openings at opposite sides, there being in the stud circular 60 grooves communicating with the bearing openings and guideways extending outwardly parallel with the axes of the bearings from the circular grooves to the ends of the stud, a handle having terminals with pins for movement in the guideways and for rotating in the circular grooves, and means for securing the other frame relatively to the stud.

5. A bag having two frame members, a stud secured to one of the frame members and provided with bearing openings at opposite sides, there being in the stud circular 65 grooves communicating with the bearing openings and guideways extending outwardly from the circular grooves, a hollow handle having terminals normally disposed in the bearing openings, pins on the terminals normally disposed in the circular 70 grooves and adapted for movement in the guideways, there being in the stud a recess extending through the outer surface of the stud and a guideway extending from the recess to one of the bearing openings, a tongue on the other frame member for movement in the recess, and a bolt member in the hollow handle for movement in the last mentioned guideway and into the opening in the tongue.

In witness whereof I have signed my name to this specification in the presence of two subscribing witnesses.

JOHAN PARTMANN.
